WIRE STRAPPING TOOL

Filed July 11, 1946

UNITED STATES PATENT OFFICE

2,594,891

WIRE STRAPPING TOOL

Harold K. Embree, Hamilton, Ontario, Canada,
assignor to Griplock, Inc., Hoboken, N. J., a corporation of Delaware

Application July 11, 1946, Serial No. 682,973

15 Claims. (Cl. 254—51)

1

This invention relates to a wire strapping tool designed for tensioning and fastening around packages straps composed of wire or the like; and it is particularly intended to be used in combination and cooperation with a wire strap which has been formed with one end of the wire turned back and coiled around the body of the wire so that the knot or fastening may be made by passing the other end of the wire strap through the said coil and then crushing or flattening the coil so as to deform it and the parts of the wire strap therewithin into a firm interlocking engagement. Simultaneously with this knotting of the strap, the excess of its free end is severed, to improve the appearance of the result, and to eliminate the long end which might present a hazard in subsequent handling and shipment.

The purpose of the invention is to provide certain novel and improved features in the structure and arrangement of the tool shown in application for United States Patent filed by Burton L. Watt and myself on February 3, 1945, Serial No. 576,054, now Patent No. 2,442,679 dated June 1, 1948; which said tool was an improvement upon that shown in United States Patent of Burton L. Watt and James J. Smith, No. 2,124,991, issued July 26, 1938.

More particularly, the invention relates to the tensioning function of the tool, with the object of providing means whereby a predetermined tension will be uniformly applied to successive straps regardless of the strength of or effort applied by the operator.

Another object is to provide means which will enable the tension operating lever, or the like, to be brought to its at rest position following the attainment of the predetermined tension, without affecting the tension and regardless of the position of the lever at the moment.

Another object is to provide means for adjusting the parts which cooperate in producing the tension so that various degrees of tension may be fixed in accordance with the requirements relating to the characteristics of the package, the strength of the strap, shipping conditions, etc.

A further object is to provide certain improvements in the form, construction and arrangement of the parts whereby the above named and other objects inherent in the construction may be effectively attained and the general efficiency of the tool increased.

Practical embodiments of the invention are shown in the accompanying drawings, in which

Fig. 1 represents a top plan view of the tool, partly broken away;

Fig. 2 represents a side elevation of the tool, partly broken away, in association with the ends

2

of the wire strap which are in operative position preliminary to the steps of tensioning, knotting, and severing the surplus wire;

Fig. 3 represents an enlarged detail section, partly in elevation, of the preferred form of slip drive mechanism for rendering the tensioning means ineffective after the predetermined tension has been attained;

Fig. 4 represents a partly broken section taken in the plane of the line IV—IV of Fig. 3, looking in the direction of the arrows;

Fig. 5 represents a view similar to Fig. 3, but showing a modified form of mechanism;

Fig. 6 represents a view similar to Fig. 3, but showing a second modified form of mechanism;

Fig. 7 represents a detail side elevation, partly in section, of a third modified form of mechanism for the same purpose;

Fig. 8 represents a view similar to Fig. 7, with certain parts shown in different positions; and

Fig. 9 represents a section taken in the plane of the line IX—IX of Fig. 8, looking in the direction of the arrows.

The tool which constitutes the subject matter of this invention is of that class designed for cooperative use with wire straps such as hereinabove described, in order rapidly and securely to bind packages which may consist of a group or pile of separate articles, or a container in which articles have been placed, or any other form of package around which it is desired firmly to clasp a binding element. The tool is adapted to be associated with a package around which such a wire strap has been loosely placed, and it includes mechanism for thereupon tensioning or binding the strap, and thereafter deforming the coiled end and contacting parts of the strap by a crushing pressure to form the desired knot which fastens the strap in its tensioned condition, with simultaneous severing of the excess or surplus end of the strap.

Those portions of the strap with cooperate with and are acted upon by the tool are shown in Fig. 2, where the body of the strap is denoted by A; its coil by B; and its end, which is passed through the coil for knotting and subsequent severing of the excess, is marked C. It will be understood that the broken away part of the strap which is not seen in the figure consists of the main body thereof which has been passed around the package before the tool has been placed in operative position.

To a substantial extent the main elements of the tool are similar in form, arrangement and operation to corresponding elements disclosed in the above named Patent No. 2,124,991, and application Ser. No. 576,054 and, as the said elements,

their mutual arrangement, and operation are fully shown and described in the said patent and application, and to that extent constitute no part of the present invention, the present description will not go into detail with respect thereto but will rely upon reference to said patent and application as an adequate disclosure thereof. However, the elements will be identified by name and general function and numbered to correspond with said patent and application in order to establish a background for detailed description of the present inventive features.

The tool comprises a base 1 which has integrally formed therewith an uprising web 2 which forms a support for a head 3 that provides a 15 housing and bearings for certain of the operative elements.

The gripping mechanism which seizes the body A of the wire at a point adjacent the coil B during the tensioning step, includes a serrated jaw 4 which is secured to the side of base 1 by screws such as 5, and cooperates with a movable jaw 6 which is arranged to be slid into and out of operative relationship with respect to the fixed jaw 4 by an arm 10 that is controlled by a hand lever 19, as is fully described in said Patent 2,124,991.

Referring to the form of the invention shown in Figs. 1 to 4, a tensioning hub 21 is journaled in extensions 22 and 23 that are integral with and connect the base 1 and head 3; extension 22 serving as a direct bearing for the hub 21, while extension 23 acts through a cup 24 which is fitted therein and has a central hole that embraces a stem 25 which is integral with and extends rearwardly from the hub 21. Teeth 46 project laterally from the face of hub 21 and are intended to receive between them the free end C of the wire strap, which latter also passes through a hook 37 that is carried by the movable jaw 6 and located intermediate the tensioning hub 21 and the point at which the knotting and severing of the strap takes place; said hook 37 serving the purpose of urging the strap into engagement with teeth 46 on hub 21.

A bored ratchet wheel 20 is located adjacent to and in surface contact with hub 21, and is arranged to be actuated by a spring pawl 47 which is bolted to the hand lever 19, and to be held against opposite motion by a spring pressed pawl 48 that is screwed on the web 2. The hand lever 19 is journaled on a reduced rearward extension of ratchet wheel 20 for manual oscillation thereabout to cause pawl 47 to actuate wheel 20.

Within the bore of the ratchet wheel are positioned two sets of annular metallic friction discs 100, 101 which are arranged in alternate sequence, the discs 100 having peripheral lugs 102 fitted into corresponding grooves 103 formed in ratchet wheel 20, and the discs 101 having lugs 104 on their inner circumferences fitted into corresponding grooves 105 formed in the stem 25 of tensioning hub 21. A series of flat, annular washers 106 are interposed between the discs 100, 101 and between the discs and the hub 21 and cup 24, which washers may be composed of fibre, leather, or other suitable material, and serve to cushion and render more efficient the action of the discs.

A short but strong expansion coil spring 107 is set in the cup 24 and is held in position by a nut 108 which is threaded on the extremity of stem 25 and is provided with recesses 109 for turning by a spanner. Thus the discs and washers are compressed between the hub 21 and the cup 24,

and the degree of compression and, hence, the degree of frictional contact between the discs and washers, may be increased or decreased by screwing the nut 108 inwardly or outwardly to vary the pressure of the cup on the discs.

As a result of the arrangement hereinabove described, manual reciprocation of the lever 19 will rotate the ratchet wheel 20 and the discs 100 which are engaged therewith, while the frictional contact of the latter, through the washers 106, will likewise rotate the discs 101 and the stem 25 with which the discs 101 are engaged, whereby the tensioning hub 21, which is integral with stem 25, will be functionally actuated.

It is customary practice for the operator to pass the wire strap loosely around the package to be bound and lead the free end C through the coil B. Thereupon, the tool is placed upon the package and moved at first laterally until its operative parts are correctly in line with the strap, and then to the left (Fig. 2) until the coil B abuts a stop 49 to insure that the coil and end of the strap to be severed are exactly in place for the crushing or knotting and severing, as is more fully described in the above named Patent No. 2,124,991. The free end C is then passed through the hook 37 and between teeth 46 on the hub 21, to bring the parts to the position shown in Fig. 2 in readiness for tensioning of the strap.

The lever 19 is then raised to cause the jaw 6 to grip the body A of the strap, as explained in the above mentioned patent, following which the operator reciprocates the said lever and the resultant rotation of the hub 21 gradually increases the tension or tightness of the strap around the package, which procedure continues until the degree of tension equals or slightly exceeds the degree of frictional resistance to relative movement of the discs 100 with respect to the discs 101. At this point, the discs 100 which are engaged with the ratchet wheel 20 begin to slip and fail to drive the discs 101 which are engaged with the stem 25 of the hub 21, so that the latter ceases to rotate and further reciprocation of the lever 19 has no effect upon the tension of the strap. The operator at once senses this condition, brings the lever 19 to its at rest position, shown in Fig. 2, and proceeds to actuate other parts of the tool for the purpose of knotting the strap and severing its excess extremity, all of which is described in said Patent 2,124,991, and will not be detailed herein as it constitutes no part of the present invention.

Important considerations relative to attainment of the best effect in binding and reinforcing packages with these straps include the proper strength of the knot formed by crushing the coil of the strap, and the proper tension of the strap when knotted. The mechanism above set forth achieves a remarkable advance in the perfection of the tensioning function, because the frictional resistance of the discs 100, 101 can be predetermined and fixed by the degree to which the nut 108 is caused to bear upon the cup 24 and, once this has been fixed, the successive straps will all receive the same tensioning regardless of variations in skill, physical strength, care, fatigue, etc. of the same or different operators. In other words, the human equation is practically eliminated and the desired tension is uniformly attained without danger of damaging the package or rupturing the strap. It should also be noted that, when the predetermined tension has been reached and the discs 100, 101 begin to slip, the operator can move the lever 19 to its at rest

position without increasing the tension on the strap, regardless of the position of the lever at the moment.

While the desired predetermined degree of frictional resistance of the discs 100, 101 is initially obtained by direct pressure of the nut 108 on the cup 24, which latter bears directly on the discs, the spring 107 is functionally valuable because it compensates for slight wear of the discs and their washers 106 by forcing the nut 108 outwardly and causing the hub 21 to compress the discs and washers together, thus maintaining constant their originally established resistance.

In the modified form of the invention shown in Fig. 5, the discs 100, 101 and their washers 106 are substituted by a bored truncated cone 113 which is fitted on the stem 25 of the hub 21 and slidably fixed thereto by a key 114; while the bore of ratchet wheel 20 is tapered to receive the cone 113. A washer 112, of fibre or other suitable material, is inserted between the hub 21 and the ratchet wheel 20.

The operative frictional resistance is obtained in this form of the invention by the contact between cone 113 and the correspondingly tapered bore of ratchet wheel 20; the nut 108 and spring 107 function as in the form of the invention shown in Fig. 3; and the tool is handled and operated as previously described.

The second modified form of the invention shown in Fig. 6, has a pair of bored truncated cones 113, 114 in place of cone 110, which cones 113, 114 are slidably fixed to the stem 25 of the hub 21 by a key 115; and the bore of the ratchet wheel 20 is reversely tapered to conform to the cones 113, 114. Here the frictional resistance is derived from the contact of the cones with the ratchet wheel, while the associated parts act as hereinbefore described.

With reference to the third modified form of the invention shown in Figs. 7, 8 and 9, the construction, arrangement and operation of the tensioning hub 21 and associated parts is as set forth in the previously named U. S. Patent application Serial Number 576,054, and the functional benefits of the present invention result from the construction and operation of the lever 19, which is here composed of two parts 116, 117, which are pivotally connected, as indicated at 118.

Lugs 119, 120, are formed integrally with the parts 116, 117 respectively, and the said lugs are perforated to receive eye bolts 121, 122, which have their shanks threaded for cooperation with nuts 123 and 124, that serve to adjust the bolts in the lugs. A powerful retractile coil spring 125 has its ends bent in hook form for engagement with the eye bolts 121, 122; the tension of the spring urging the parts 116, 117 of the lever to the position shown in Fig. 7, and against movement about the pivot 118 to the position shown in Fig. 8. A shield or guard 126 is secured to the lever part 117 by bolts 127 to protect the spring 125 and the operator.

In the use of this form of the invention, the nuts 123 and/or 124 are adjusted to impart to the spring 125 the desired resistance to movement of the lever part 117 about pivot 118. The lever 19 is then reciprocated to rotate the hub 21 and tension the strap, as previously explained, and, when the predetermined tension has been reached, the spring 125 will yield and permit the lever part 117 to move on the pivot 118 from the position shown in Fig. 7 to or toward the position shown in Fig. 8, or beyond the last named position. This will terminate the rotative effect of

the lever 19 upon the hub 21, and the operator will become aware that the predetermined tensioning of the strap has been attained so that he may proceed to the activation of other elements of the tool for knotting the strap and serving its excess end.

It will be seen that this invention provides for accomplishment of package strapping with uniformity in tension of the straps, according to predetermined standard, regardless of variations in any or all factors that contribute to the operation of the tool; as a result of which proper reinforcement of the packages is insured and breakage of straps and injury to packages is eliminated or, at least, greatly minimized.

It will also be understood that various changes may be resorted to in the form, construction and arrangement of the parts without departing from the spirit and scope of the invention; and hence I do not intend to be limited to details herein shown or described except as they may be included in the claims or required by disclosures of the prior art.

What I claim is:

1. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one friction clutch member surrounding and engaged with said stem, at least one other friction clutch member surrounding said stem and engaged with the rotating means, and means on said stem for holding said clutch members in frictional contact.

2. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one friction clutch member surrounding and engaged with said stem, at least one other friction clutch member surrounding said stem and engaged with the rotating means, positively acting means on said stem for holding the said clutch members in frictional contact, and yielding means on said stem for maintaining said frictional contact by taking up wear between said members.

3. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for

causing operation of the latter to rotate said element until the tension of the strap resulting from the pulling of said element thereupon reaches a predetermined degree while permitting the operation of said rotating means to become ineffective thereafter, said intermediate means comprising at least one friction clutch member surrounding and engaged with said stem, at least one other friction clutch member surrounding said stem and engaged with the rotating means, positively acting means on said stem for holding the said clutch members in frictional contact, and yielding means on said stem for maintaining said friction contact by taking up wear between said members, said means for holding the said clutch members in frictional contact and taking up wear therebetween including a nut threaded on said stem, a rigid element interposed between and in contact with said nut and a said clutch member and a resilient element interposed between said nut and said rigid element.

4. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one friction clutch member surrounding and engaged with said stem, at least one other friction clutch member surrounding said stem and engaged with the rotating means, positively acting means on said stem for holding the said clutch members in frictional contact, and yielding means on said stem for maintaining said frictional contact by taking up wear between said members, said means for holding the said clutch members in frictional contact and taking up wear therebetween including a nut threaded on said stem, a rigid cup-shaped element interposed between and in contact with said nut and a said clutch member and an expansion spring housed in said cup-shaped element and bearing against it and said nut.

5. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one friction clutch disc surrounding and engaged with said stem, at least one other friction clutch disc surrounding said stem and engaged with the rotating means, and means on said stem for holding said clutch members in frictional contact.

6. In a tool of the character described, mechanism for tensioning a strap around a package, said mechanism including a rotatable element for engaging and pulling the strap, a stem projecting

co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one friction clutch disc surrounding and engaged with said stem, at least one other friction clutch disc surrounding said stem and engaged with the rotating means, positively acting means on said stem for holding the said clutch members in frictional contact, and yielding means on said stem for maintaining said frictional contact by taking up wear between said members.

7. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one conical clutch member surrounding and engaged with said stem, at least one other conical clutch member surrounding said stem and engaged with the rotating means, and means on said stem for holding said clutch members in frictional contact.

8. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising at least one conical clutch member surrounding and engaged with said stem, at least one other conical clutch member surrounding said stem and engaged with the rotating means, positively acting means on said stem for holding the said clutch members in frictional contact, and yielding means on said stem for maintaining said frictional contact by taking up wear between said members.

9. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising a plurality of conical clutch members surrounding and

engaged with said stem, a complementarily shaped clutch member surrounding said stem and engaged with the rotating means, and means on said stem for holding said clutch members in frictional contact.

10. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising a plurality of conical clutch members surrounding and engaged with said stem, a complementarily shaped clutch member surrounding said stem and engaged with the rotating means, positively acting means on said stem for holding the said clutch members in frictional contact, and yielding means on said stem for maintaining said frictional contact by taking up wear between said members.

11. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising a plurality of oppositely tapered conical clutch members surrounding and engaged with said stem, a complementarily shaped clutch member surrounding said stem and engaged with the rotating means, and means on said stem for holding said clutch members in frictional contact.

12. In a tool of the character described, mechanism for tensioning a strap around a package, said mechanism including a rotatable element for engaging and pulling the strap, a stem projecting co-axially from said element, operable rotating means surrounding said stem for imparting rotation to said element, and means intermediate said stem and said rotating means for causing operation of the latter to rotate said element until the tension of the strap resulting from the pulling of said element thereupon reaches a predetermined degree while permitting the operation of said rotating means to become ineffective thereafter, said intermediate means comprising a plurality of oppositely tapered conical clutch members surrounding and engaged with said stem, a complementarily shaped clutch member surrounding said stem and engaged with the rotating means, positively acting means on said stem for holding the said clutch members in frictional contact, and yielding means on said stem for maintaining said frictional contact by taking up wear between said members.

13. In a tool of the character described, mechanism for tensioning a strap around a package,

said mechanism including a rotatable element for engaging and pulling the strap, a stem projecting co-axially from said element, a bored rotatable ratchet surrounding said stem for imparting rotation to said element, and means within the bore of said ratchet for causing operation of the latter to rotate said element until the tension of the strap resulting from the pulling of said element thereupon reaches a predetermined degree while permitting the operation of said ratchet to become ineffective thereafter, said last named means comprising at least one friction clutch member surrounding and engaged with said stem, at least one other friction clutch member engaged with the bore of said ratchet, and means for holding said clutch members in frictional contact.

14. In a tool of the character described, mechanism for tensioning a strap around a package, 20 said mechanism including a rotatable element for engaging and pulling the strap, a stem projecting co-axially from said element, a conically bored rotatable ratchet surrounding said stem for imparting rotation to said element, and means 25 within the bore of said ratchet for causing operation of the latter to rotate said element until the tension of the strap resulting from the pulling of said element thereupon reaches a predetermined degree while permitting the operation of 30 said ratchet to become ineffective thereafter, said last named means comprising at least one conical clutch member surrounding and engaged with said stem, and means for holding said clutch member in frictional contact with the bore of 35 the ratchet.

15. In a tool of the character described, mechanism for tensioning a strap around a package, said mechanism including a rotatable element for engaging and pulling the strap, a stem projecting co-axially from said element, a reversely conically bored rotatable ratchet surrounding said stem for imparting rotation to said element, and means within the bore of said ratchet for causing operation of the latter to rotate said element until the tension of the strap resulting from the pulling of said element thereupon reaches a predetermined degree while permitting the operation of said ratchet to become ineffective thereafter, said last named means comprising a 40 pair of oppositely tapered conical clutch members surrounding and engaged with said stem, and means for holding said clutch members in frictional contact with the bore of the ratchet.
